J. SETTERBERG

LOCK

Filed July 14, 1924

J. Setterberg

INVENTOR

BY *Victor J. Evans*

ATTORNEY

UNITED STATES PATENT OFFICE.

JOSEPH SETTERBERG, OF CHICAGO, ILLINOIS.

LOCK.

Application filed July 14, 1924. Serial No. 725,946.

To all whom it may concern:

Be it known that I, JOSEPH SETTERBERG, a citizen of the United States, residing at 3229 W. North Ave., Chicago, in the county 5 of Cook and State of Illinois, have invented new and useful Improvements in Locks, of which the following is a specification.

This invention relates to new and useful improvements in locks and more particularly to a lock which is especially adapted for use on spare tires for motor vehicles. The main object of my invention is the provision of a lock which is to be attached to one end of a tire lock chain and adapted to 10 receive and retain in position a locking bolt which is attached to the other end of the chain, thus securely locking the tire upon the rack for supporting the spare tire.

Another object of the present invention 20 is the provision of a novel type of lock of this character wherein the bolt is provided with a plurality of annular shoulders and adapted to be inserted within a bore formed in the body of the lock, suitable tumblers 25 within the body engaging the shoulders on the bolt to prevent removal of the bolt until the tumblers have been actuated to disengage the same from the shoulders.

With the above and other objects in view, 30 the invention consists in the novel features of construction, the combination and arrangement of parts hereinafter more fully set forth, pointed out in the claims and shown in the accompanying drawings, in 35 which:

Figure 1 is the perspective view illustrating the application of my improved lock,

Figure 2 is a longitudinal section through 40 the body of the lock, illustrating the cooperating parts in elevation.

Figure 3 is a view similar to Figure 2, illustrating the tumblers in longitudinal section,

Figure 4 is an enlarged perspective view 45 of one of the tumblers, and

Figure 5 is a detailed sectional view on the line 5—5 of Figure 3.

In carrying out my invention, I prefer to use my improved lock with a locking chain 50 1 which, in the present instance, is attached to the pneumatic tire 2 of a motor vehicle, as clearly illustrated in Figure 1. The ends of the chain 1 are provided with eyes 3 and attached to one of the eyes at one end of the chain is a perforated ear 4 formed integral 55 with the body 5 of my improved lock.

The body 5 of my improved lock is provided with two inwardly extending bores 6 and 7, said bores extending into the body at right angles to each other and their pathway meeting at preferably the central portion of the body, as is clearly illustrated in Figure 2. Arranged within the bore 7 are the tumblers 8 and 9, the tumbler 8 being arranged at the inner end of the bore 7 and normally retained in spaced relation with the inner end of the bore by means of a coil spring 10. The tumbler 9 is positioned within the outer end of the bore 7 and retained in an operative position by means of the annular flange 11 having a groove 12 in which the bearing ring 13 is arranged, said flange and ring being embedded within the material of which the body 5 is formed, as shown in Figure 2, so as to prevent the 75 tumbler 9 from being withdrawn from the bore. The tumbler 8 is provided with a slightly curved end which faces the bore 6 and is further provided in this curved end with a plurality of ribs 14 and the projecting lips formed by the curved end of the tumbler are provided with recesses 15 into which the inner ends of the pins 16 engage for imparting movement to the tumbler 8 upon rotation of the tumbler 9, the other 80 ends of the pins 16 bearing against the flange 17 formed on the inner end of the tumbler 9 and adapted to ride onto the shoulders 18 for moving the tumbler 8 against the tension of the spring 10. Suitable 85 stops 19 are formed adjacent the shoulder 18 to limit the turning movement of the tumbler 9, the ends of the pins 16 striking the stops 19.

These pins described above are preferably 90 arranged within longitudinal channels 20 formed in opposed relation in the wall of the bore 7 with their ends engaging the tumblers as set forth above. The tumbler 9 is provided with a key way 21 into which 100 the proper key may be fitted for rotating the tumblers 9 as set forth above.

The eye 3 opposite the body 5 has attached thereto a connecting bolt 22, the outer end of which is provided with a plurality of annular flanges 23, said connecting bolt adapted to be inserted into the bore 6 and with pressure forced over the ribs 14 on the locking bolt 8, but as the ribs 23 on the bolt 22 are tapering and provided with horizontal faces, they will engage with the horizontal faces of the tapering ribs 14 and pre-

vent withdrawal of the bolt 22 until the tumbler 9 has been actuated by a suitable key for engaging the ends of the pins 16 with the shoulders 18 and reciprocating the bolt 8 against the tension of the spring 10, which movement will move the shoulders 14 out of the path of the shoulders 23 on the bolt 22 and permit the bolt 22 to be withdrawn from the bore 6.

10 From the above, it will be apparent that I have provided a simple, inexpensive, and durable lock of this character whereby a retaining chain for motor vehicle tires may be quickly and readily placed in position and 15 its ends connected to retain the same upon the rack. This lock will also prevent the removal of the tire from the wheel rack by unauthorized persons. It will also be apparent that the lock is extremely effective 20 for articles of this type and can be made in various shapes.

While I have shown and described the preferred embodiment of my invention, it will be understood that various changes and 25 alterations may be made without departing from the spirit of the invention or the scope of the appended claims.

Having thus described my invention, what I claim is:

30 1. A lock of the character described, including a body having a longitudinal and transverse bore extending into the body with their inner ends crossing each other, a connecting bolt having annular shoulders upon 35 its outer end and adapted to be inserted into

the longitudinal bore and extended across the transverse bore, a spring pressed locking tumbler having a ribbed face to cooperate with the shoulders on the bolt for retaining the bolt in a locked position, and a key operated tumbler within the transverse bore co-operating with the first tumbler to release said bolt.

2. A lock of the character described, including a body having a longitudinal and transverse bore, a locking bolt having a plurality of shoulders upon its outer end adapted to be inserted into the longitudinal bore, a spring pressed locking tumbler within the inner end of the transverse bore having normal locking engagement with the shoulders on the bolt, a key operated tumbler in the outer end of the transverse bore, and means forming operative connection between the said tumblers whereby rotation of the key operated tumbler will disengage the locking tumbler from the bolt.

3. A lock of the character described including a body having a longitudinal and transverse bore, a locking bolt in the longitudinal bore, a spring pressed locking tumbler in the transverse bore having locking engagement with the said bolt, a key operated tumbler in the outer end of the transverse bore and means forming operative connection between the said tumblers whereby rotation of the key operated tumbler will disengage the locking tumbler from the bolt.

In testimony whereof I affix my signature.
JOSEPH SETTERBERG.
